Fig. 11

FIGURE 9 is a side view of the same (opposite sides being similar in appearance);

FIGURE 11 is a rear view of the same.

The dominant features of my design reside in the portions shown in full lines, the broken line drawing of wheels being omitted in some figures for convenience of illustration.

I claim:

The ornamental design for a coaster wagon, substantially as shown and described.
